JOE H. NICKS AND ELLERY E. MOSHER, OF CORPUS CHRISTI, TEXAS

BLOW-OUT PREVENTER ATTACHMENT

Application filed April 16, 1931, Serial No. 530,650. Renewed October 14, 1932.

This invention relates to an improved attachment for blow-out preventers and particularly to an attachment of the type described which has the features of novelty 5 and advantage which will be more fully understood as the description thereof proceeds below.

It is an object of this invention to provide an attachment of the type described which is not only simple to operate and install, but which is composed of few and rugged parts, which are easily and quickly manipulable, and which can be produced at a relatively low cost and attached to certain types 10 of standard blowout preventer heads, and may, with slight modification, be attached to any type of blow-out preventer head or casing employing the ram type of structure.

These and other objects of the invention, 15 its nature, its composition and arrangement and combination of parts will be readily understood by anyone acquainted with the art to which this invention relates upon consulting the following descriptions of the drawings, in which:—

Figure 1 is a side elevational view of the attachment in place on a standard blow out preventer head or casing.

Figure 2 is a vertical longitudinal sectional view through Figure 1 disclosing the rams in retracted position.

Figure 3 is a view similar to Figure 2 except that the rams are shown in extended position.

Figure 4 is a horizontal sectional view approximately on the line 4—4 of Figure 1 looking downwardly.

Referring in detail to the drawings, the numeral 5 generally designates a standard type of blow-out head or casing comprising 40 the horizontal cylinder 6 in which slide the rams 7, and the numeral 8 refers to the upward extension of the head or casing 5 and the numeral 9 refers to the downward extension of the casing 5, the extensions 8 and 9 45 communicating with the interior of the cylinder 6. The ends of the cylinder 6 are interiorly screw-threaded as indicated at 10 to receive a cylindrical, flanged block 11. The block 11 has a lateral flange 12 for abutting 50 the end of the cylinder 6, inwardly of

which is a flange 13 exteriorly screw-threaded to engage the interior threads 10 in the end of the cylinder 6. The block 11 has in its outward end a screw-threaded recess 14 adapted to receive a screw-threaded nipple 55 15 on the inwardly disposed end of a block 16 which has a hollow nipple 17 on its outwardly disposed end, the nipple 17 being both exteriorly and interiorly screw-threaded. Threaded upon the exterior screw threads of 60 the nipple 17 is the inward end of a sleeve 18 which is open at its sides as indicated at 19 and provided with a large screw-thread interiorly of its outward end as indicated at 20. Within the sleeve 18 is a tubular nut 21 65 adapted to be received in the outwardly disposed end of the block 16 to compress a packing 22 in the recessed end of the block 16. Adapted for inward and outward movement 70 through the block 11, the block 16, the tubular nut 21 and the sleeve 18, is a shaft generally designated 23 having its inward end reduced and screw-threaded as at 24 into one of the rams 7. An intermediate portion of the shaft designated 25 is enlarged and forms 75 shoulders 26, 27, the shoulder 27 being formed by another plane reduced portion 28 outward of the enlarged portion 25. It will also be noted that the outward end portion of the shaft 23 is further reduced as at 29 and 80 squared at 30 for receiving appropriate turning means. It has yet to be stated that 85 slideable upon the plane portion 28 of the shaft 23 is a large tubular exteriorly screw-threaded nut 31 for screw-threadedly engaging the interior screw-threads 20 in the outward end of the sleeve 18. Suitable means suggested at 32 may be provided for rotating the tubular nut 31 so as to bring it into engagement with the shoulder 27 on the outward end of the enlarged portion 25 for forcing the shaft inwardly through the packing nut 21, the block 16 and the block 11, whereby to push the adjacent ram 7 inwardly in well known manner. It should further be stated that the blocks 11 90 95 are provided at their undersides with a fluid passage 33 with suitable piping 34 for conveying fluid under pressure into the cylinder 6 behind the rams 7 for forcing them inwardly against the pressure of a blowing out 100

well to close the preventer to prevent blowing of the tools and the loss of the flow of the well.

It will be obvious that the structure described incorporates the large tubular nut 31 which constitutes a very important improvement in devices of this kind, and which is adapted to lock the ram in extended, blow-out preventing position. It will be further evident that turning the shaft 23 independently of the movement of the locking nut 31 will result in positioning the ram 7 either inwardly or outwardly with respect to the vertical passage of the blow-out head or casing. It will be observed that the locking nut 31 is provided with the flange or shoulder 35 for preventing the possibility of its being screwed completely out of the sleeve 18. Of course, the packing nut 21 functions in an obvious manner to compress the packing 22 about the enlarged portion 25 of the shaft 23 so as to prevent the escape of fluid. It will also be observed that the shoulder 26 on the enlarged portion 25 of the shaft 23 in the said cases adapts it to abut the shoulder 36 of the ram 7. The packing nut 21 is easily reached through the opening 19 in the sleeve 18, radial holes 36 being provided in the periphery of the flanged portion of the packing nut to permit insertion of a turning tool.

In Figures 1, and 4 appear stud bolts 38 which project radially through the side of the cylinder 6 for engaging in a groove in each of the rams 7 for preventing turning of the rams in the operation of rotation of the shaft 23.

Inasmuch as each side of the preventer attachment described herein is identical in construction, the description of one is deemed sufficient to describe the other, it being understood that one is useless without the other and that they cooperate to bring about the result sought.

It is to be definitely understood that we do not desire to limit the application of this invention to the particular modification set out herein to illustrate the principles thereof, and any change or changes may be made in materials and arrangement of parts in the structure consistent with the spirit and scope of the invention.

What is claimed is:—

1. A blow-out preventer of the type described comprising in combination a standard ram head having the ends of its horizontal cylindrical portions interiorly screw-threaded, a cylindrical block screw-threaded into each of the said horizontal portions having in turn screw-threaded thereinto another block having shaft packing means in its outward end, a shaft slidable through said blocks, a hollow sleeve screw-threaded to extend axially outward from said other block the outward end portion of which is interiorly screw-threaded, a locking nut slidable on a reduced portion of said shaft and engageable with said interiorly screw-threaded portion of the sleeve and adapted to be rotated to abut a shoulder formed by said reduced portion of the shaft with the balance of the shaft to prevent outward movement of the shaft, said shaft being connected at its inner end with one of the rams in the ram head.

2. A blow-out preventer of the type described comprising in combination a standard ram head having the ends of its horizontal cylindrical portions interiorly screw-threaded, a cylindrical block screw-threaded into each end of the said horizontal portions having in turn screw-threaded thereinto another block having shaft packing means in its outward end portion of which is interiorly screw-threaded, a locking nut slidable on a reduced portion of the shaft and engageable with said interiorly screw-threaded portion of the sleeve and adapted to be rotated to abut a shoulder formed by said reduced portion of the shaft with the balance of the shaft to prevent outward movement of the shaft, said shaft being connected at its inner end with one of the rams in the ram head.

3. A blow-out preventer of the type described comprising in combination a standard ram head having the ends of its horizontal cylindrical portions interiorly screw-threaded, a cylindrical block screw-threaded into each end of the said horizontal portions having in turn screw-threaded thereinto another block having shaft packing means in its outward end portion of which is interiorly screw-threaded, a locking nut slidable on a reduced portion of the shaft and engageable with said interiorly screw-threaded portion of the sleeve and adapted to be rotated to abut a shoulder formed by said reduced portion of the shaft with the balance of the shaft to prevent outward movement of the shaft, said shaft being connected at its inner end with one of the rams in the ram head, said inner end of the shaft being reduced and screw-threaded to engage in the ram, and the shaft having means at its outer end for rotating the same to move the ram independently of the locking nut.

4. A blow-out preventer of the type described comprising in combination a standard ram head having the ends of its horizontal cylindrical portions interiorly screw-threaded, a cylindrical block screw-threaded into each end of the said horizontal portions having in turn screw-threaded thereinto another block having shaft packing means in its outward end, a shaft slidable through said blocks, a hollow sleeve screw-threaded to extend axially outward from said other block the outward end portion of which is interiorly screw-threaded, a locking nut slidable on a reduced portion of said shaft and engageable with said interiorly screw-threaded portion of the sleeve and adapted to be rotated to abut a shoulder formed by said reduced portion of the shaft with the balance of the shaft to prevent outward movement of the shaft, said shaft being connected at its inner end with one of the rams in the ram head, said inner end of the shaft being reduced and screw-threaded to engage in the ram, and the shaft having means at its outer end for rotating the same to move the ram independently of the locking nut, and a fluid connection through each of said cylindrical blocks communicating with the interior of the ram head for introducing fluid under pressure behind each of said rams.

4. A blow-out preventer of the type described comprising in combination a standard ram head having the ends of its horizontal cylindrical portions interiorly screw-threaded, a cylindrical block screw-threaded into each end of the said horizontal portions having in turn screw-threaded thereinto another block having shaft packing means in its outward end, a shaft slideable through said blocks, a hollow sleeve screw-threaded to extend axially outward from said other block the outward end portion of which is interiorly screw-threaded, a locking nut slideable on a reduced portion of said shaft and engageable with said interiorly screw-threaded portion of the sleeve and adapted to be rotated to abut a shoulder formed by said reduced portion of the shaft with the balance of the shaft to prevent outward movement of the shaft, said shaft being connected at its inner end with one of the rams in the ram head, said inner end of the shaft being reduced and screw-threaded to engage in the ram, and the shaft having means at its outer end for rotating the same to move the ram independently of the locking nut, said locking nut having a flange at its inward end for preventing screwing rotating the locking nut out of the sleeve.
5. A blow-out preventer of the type described comprising in combination a standard ram head having the ends of its horizontal cylindrical portions interiorly screw-threaded, a cylindrical block screw-threaded into each end of the said horizontal portions having in turn screw-threaded thereinto another block having shaft packing means in its outward end, a shaft slideable through said blocks, a hollow sleeve screw-threaded to extend axially outward from said other block the outward end portion of which is interiorly screw-threaded, a locking nut slideable on a reduced portion of said shaft and engageable with said interiorly screw-threaded portion of the sleeve and adapted to be rotated to abut a shoulder formed by said reduced portion of the shaft with the balance of the shaft to prevent outward movement of the shaft, said shaft being connected at its inner end with one of the rams in the ram head.

In testimony whereof we affix our signatures.

JOE H. NICKS.
ELERY E. MOSHER.
